CLAIM

The ornamental design for an atmospheric water generator, as shown and described.

DESCRIPTION

FIG. 1 is a top front left perspective view of the new design for an atmospheric water generator,

FIG. 2 is a back view of FIG. 1,

FIG. 3 is a front view of FIG. 1,

FIG. 4 is a right side view of FIG. 1,

FIG. 5 is a left side view of FIG. 1; and,

FIG. 6 is a top view of FIG. 1.

The bottom view which is not shown in the drawings forms no part of the claimed design.

The features shown in broken lines in the drawings form no part of the claimed design.
